PICTURE FRAME

Filed Jan. 20, 1943

to draw the rollers upwardly into the extensions 20 of the slots so that the rollers with the carrier thereon is disposed immediately beneath the platens 25. After such assembly, the backing cover 34 may be fixed to the frame outwardly of the carrier and a picture thereon will be properly held before the frame opening 13. When it is desired to bring a new picture into view, the key 24 is employed for rotating the roller desired. As a roller is filled by winding the carrier thereon, the increased diameter of the roller will be accommodated by reason of the fact that the roller will tend to move downwardly through the slot 19 against the tension of the springs 33.

While I have shown and described a preferred construction, this is by way of illustration only, and I consider as my own all such modifications in construction as fairly fall within the scope of the appended claims.

I claim:

1. A carrier for picture elements and the like for successive display of the picture elements before a view opening of a frame comprising a flexible elongated support member, said support member having pairs of spaced loop members upon one side thereof, a picture element complementary to each pair of loop members, each picture element having oppositely disposed arms adapted to frictionally fit within respective pairs of loops.

2. A carrier for spaced detachable picture elements and the like comprising a flexible elongated support member, said support member having pairs of spaced loop members upon one side thereof, a picture element complementary to each pair of loop members, each picture element having oppositely disposed arms adapted to frictionally fit within respective pairs of loops.

FRANCIS D. CRICHTON.
